UNITED STATES PATENT OFFICE.

CHARLES C. RICHARDSON, OF NEW YORK, N. Y., BY PROCESS OF LAW ASSIGNOR TO
HYDROLA HEATER CORPORATION, A CORPORATION OF NEW JERSEY.

COMBINATION BURNER AND GENERATOR.

Application filed January 2, 1923, Serial No. 610,086. Renewed October 22, 1923.

To all whom it may concern:

Be it known that CHARLES C. RICHARDSON, citizen of the United States, residing at New York city, in the county of New York and State of New York, has invented certain new and useful Improvements in Combination Burners and Generators, of which the following is a specification.

The present invention relates to new and useful improvements in combination generators and burners.

The primary object of the invention resides in the provision of an apparatus such as above noted, which employs means for heating, mixing and then superheating a plurality of liquids to form a gas which is then burned in the said device, which may be installed within a heater or stove of any desired type, serving as a substitute for the customary coal or other fuel now used.

Another object of the invention is the provision of an apparatus such as above referred to, which consists of a series or plurality of detachable counterpart units, which may be added to or taken away from as desired to accomodate the device to stoves of different sizes, thereby increasing or decreasing the volume of heat produced in accordance with the necessary requirements.

A further object of the present invention resides in the provision of a combination burner and generator, which will be comparatively simple and inexpensive to manufacture, reliable and efficient in use, and readily operated.

With the above and other objects in view, the present invention resides in the certain novel features of construction, formations, combinations and arrangements of parts to be hereinafter more fully described, claimed and illustrated in the accompanying drawings in which:

Figure 1 is a diagrammatical view showing one form of installation;

Figure 2 is a perspective view of an assembly of units;

Figure 3 is a plan view of the invention;

Figure 4 is a transverse sectional view thereof;

Figure 5 is a fragmentary longitudinal sectional view showing the means of connecting the units; and,

Figure 6 is a side elevation thereof.

Referring now to the accompanying drawings by similar characters of reference

throughout the several views, the numeral 1 denotes in general a furnace which may be of any well known type, and in which my combination burner and generator is installed. This device is designated by 2 and 60 rests upon the usual grate.

This combination burner and generator consists of a boiler 4 and a plurality of units 5. The former is of elongated formation and may be of any preferred shape and 65 size, while the latter comprises a series of U-shaped members 6 having angular heads 7, the latter of which are connected by nipples 8, which connect the interior passages 9 of the said members 6, alternately at their 70 upper and lower sides as clearly shown at Figure 5.

Inlet pipes 10 and 11 lead to the boiler 4 and one of the units 5 respectively, and serve to convey water to the said boiler and 75 oil, such as fuel oil, furnace oil, kerosene and the like, to the said units. This oil and water is controlled by the valves 12 and 13. Cut-off valves 14 and 15 are also likewise employed as well as suitable drain connections 80 16 and 17.

The pipe 10 leads to a supply tank 18 for the water, while the pipe 11 leads to a tank 19 for the oil. This first mentioned tank 85 is connected with the usual supply or water line, under the control of the ball cock 20.

A flash pan 21 may be used for priming the device for starting, or gas may be piped as at 22 to the burner pipes 23 which lie under the boiler and units. The gas pipe 90 is shown at 24.

The burner pipes 23 may be connected to the units 5 at any suitable point.

In operation, the boiler and units are first heated either by means of the flash pan or 95 gas and the oil and water are turned on, the water flowing into the boiler and the oil into the units, into which the steam passes, mixing with the oil vapors. This combined mixture is mixed and super-heated 100 forming a gaseous mixture which then burns in the spaces between the boiler and units. It will be noted that the pressure forces the gas with sufficient force so that it does not burn at the openings in the burner pipes 105 but considerably above the same, hence eliminating all carbon formations that might tend to clog these said openings.

From the foregoing description taken in connection with the accompanying drawing,

it will be manifest that a combination burner and generator is provided, which will fulfill all of the necessary requirements of such a device, and it should be understood in this connection, that various minor changes in the specific details of construction can be resorted to within the scope of the appended claims without departing from the spirit or sacrificing any of the advantages of the invention.

Having thus fully described this invention, what I claim as new and desire to protect by Letters Patent is:

1. A generator unit comprising a U-shaped body portion having the ends thereof squared, the opposite side faces of said ends having an opening therein, and the opposite side faces of said unit arranged to contact with the faces of a second unit, said unit having the squared ends thereof disposed in parallel relation relative to each other.

2. A generator unit comprising a body portion having the ends thereof squared, the opposite side faces of said squared ends having an opening therein, said faces being oppositely disposed and adapted for connection to a side face of a second unit.

3. In a device such as described, the combination of a plurality of U-shaped units having squared heads and means for alternately connecting the heads of the units to form a continuous passage within the same.

4. The combination in a device such as described, of a plurality of U-shaped units having angular heads, means for alternately connecting the said heads to form a continuous passage therein, means for feeding oil and water to said units, and means for heating, vaporizing, mixing and superheating the oil and water to form a gas.

5. In a device such as described, the combination of a plurality of detachable U-shaped units arranged on edge, means for connecting the alternate ends of the units and means for feeding liquid fuel thereto to form a gas.

6. In a generator such as described, a plurality of U-shaped units having the ends of each unit arranged one above the other, and means for connecting the upper and lower ends of said units alternately to form a tortuous passage throughout the generator.

In testimony whereof I affix my signature.
CHARLES C. RICHARDSON.
